CLAIM

The ornamental designs for a cap for cosmetic and fragrance bottles, as shown and described.

DESCRIPTION

FIG. 1 is a top perspective view of our design for a cap for cosmetic and fragrance bottles;

FIG. 2 is a front view of the cap represented in FIG. 1;

FIG. 3 is a back view of the cap represented in FIG. 1;

FIG. 4 is a right side view of the cap represented in FIG. 1;

FIG. 5 is a left side view of the cap represented in FIG. 1;

FIG. 6 is a top view of the cap represented in FIG. 1; and,

FIG. 7 is a bottom view of the cap represented in FIG. 1.

The dashed lines in FIGS. 1-7 represent environmental structure and form no part of the claimed cap. All other surface(s) or portion(s) of the cap in FIGS. 1-7 not shown in figures or otherwise described in the specification form no part of the claimed cap.

1 Claim, 6 Drawing Sheets
